VALVE.

1,055,781.

Specification of Letters Patent. Patented Mar. 11, 1913.

Application filed October 23, 1911. Serial No. 656,222.

To all whom it may concern:

Be it known that we, NELSON B. MITCHELL and JOHN W. TAGGART, Sr., citizens of the United States, residing at Indianapolis, in the county of Marion and State of Indiana, have invented a new and useful Valve, of which the following is a specification, reference being had to the accompanying drawings and to the letters and figures of reference marked thereon.

This invention relates to valves of the type that is adapted for controlling the admission and discharge of steam or air in the operation of engines or other machinery, such as hoists or lifting apparatus, the invention having reference more particularly to a valve that is so constructed as to be adapted for operation either by hand or automatically by means of mechanism.

The object of the invention primarily is to provide an improved valve that may be simply and cheaply produced and also be reliable, durable and economical in use; a further object being to provide a valve of the above mentioned character that may be constructed without the use of packing-rings or springs and therefore not liable to derangement in operation.

With the above mentioned and minor objects in view, the invention consists in the rotary valve and valve chest substantially as described in our application for Letters Patent for switch operating mechanism, filed May 31, 1911, Serial No. 630,302, the invention having certain novel features of construction, and consisting further in the parts and combinations and arrangements of parts as hereinafter particularly described and claimed.

Referring to the drawings, Figure 1 is a top plan of the improved valve; Fig. 2, a vertical section on the plane of the line A A in Fig. 1; Fig. 3, a horizontal section on the plane of the line B B in Fig. 2; Fig. 4, a plan of the bottom of the valve chest; Fig. 5, a perspective view of the improved valve; Fig. 6, a fragmentary section similar to Fig. 3 but with the valve in a different position; Fig. 7, a section similar to Fig. 6 but with the valve in still another position; and Fig. 8, a fragmentary section of the valve chest on the line C C in Fig. 2.

Similar reference characters in the differ-

ent figures of the drawings indicate like elements or features of construction herein referred to.

In construction a chest bottom 1 is provided which is circular in plan and in the upper side has a depressed joint seat 2 at the outer side of which is a shoulder 3, the remaining middle portion of the bottom being flat and constituting a valve seat 4 having a cylindrical guide shoulder 5 extending about it. Two screw-threaded delivery port openings 6 and 7 are formed in the bottom of the valve seat, the openings extending from the valve seat through the bottom and are arranged at opposite sides of the center of the valve seat equi-distant therefrom. The bottom has also an exhaust port opening 8 extending therethrough from the valve seat between the openings 6 and 7. The outer portion of the bottom has a suitable number of bolt holes 9 therein. A pipe elbow 10 is screwed into the port opening 6 and an elbow 11 is screwed into the port opening 7 so that pipes may be connected thereto and connected with a cylinder or with other apparatus. A dome shaped valve chest 12 is provided which has a flange 13 on its lower portion that is seated upon the bottom 1, the under side of the chest having an annular projection 14 fitting closely against the joint shoulder 3 and seated on the joint face 2 so as to form a steam tight joint without the use of packing. A suitable number of bolts 15 are placed in the holes 9 and are suitably secured to the bottom 1 and rigidly secure the chest to its bottom. The inner side of the chest has a cylindrical guide wall 16 corresponding in diameter to the diameter of the guide shoulder 5 and continuing upwardly a suitable distance within the chest. The chest has a boss 17 on its side having an aperture in which a supply pipe 18 is screwed. The upper portion of the chest has a packing box 19 thereon in which is a gland 20 retained by a packing-nut 21.

A cylindrical valve 22 is provided that has a flat valve face 23 and is seated movably on the valve seat 4 and in contact with the guide shoulder 5 and also in contact with the guide wall 16, the back of the valve proper having an operating stem 24 secured thereto, the stem extending through

the packing box and the gland and the packing nut. The periphery 25 of the valve forms a journal for rotatively guiding the valve, and the shoulder 5 and guide wall 16 5 together constitute a journal bearing for guiding the valve. The stem 24 constitutes also a journal for guiding the valve, especially in case the valve is so arranged for use that the stem is horizontal. The end 10 portion of the stem has a tapering portion 26 on which is fitted an arm or operating handle 27, there being a washer 28 placed over the end portion and against the arm, a retaining nut 29 being screwed onto the 15 end portion of the stem against the washer for securely holding the arm on the stem, and when the nut is slackened it is evident that the arm may be readjusted relative to the stem, the arm having a hole 30 therein 20 so that an operating device may be connected thereto for automatically operating the valve if desired. The valve 22 has a central cavity 31 extending inward from the face 23 and two exhaust channels 32 and 25 33 extend from the cavity at obtuse angles so as to form communication between the opening 8 and the openings 6 and 7 during operation of the valve. The channels as will be seen extend from the axis of the 30 valve to a plane beyond one side of the axis so that full exhaust communication is had with only one of the openings 6 or 7 at a time, but permitting restricted exhaust from both openings 6 and 7 at the same time during operation of the valve. The valve has two ports 34 and 35 that extend therethrough and are so placed that they are in a plane beyond the opposite side of the axis 35 of the valve from the plane to which the 40 channels extend, and are placed the required distance away from the axis so as to be adapted to register with the opening 6 or 7 or when the valve is in a certain position permit fluid to pass into both openings 6 and 7 to a limited extent, but full passage 45 may be permitted into only one or the other of the openings 6 or 7 at one time. The chest has a guide shoulder 36 formed therein against which the rear edge portion of 50 the valve 22 is guided in case there is no fluid pressure in the valve chest, the fluid pressure in operation holding the valve to its seat.

In practical use the valve is moved to the 55 position shown in Fig. 3 for admitting the fluid (or liquid if used) from the valve chest to the port opening 7 through the port 35 and permitting exhaust to take place from the opening 6 through the channel 32 60 to the opening 8. The valve is placed in the position shown in Fig. 6 for permitting the fluid to pass from the valve chest into the opening 6 through the port 34 and permit exhaust to take place from the opening 65 7 through the channel 33 to the opening 8.

The rotary movement of the valve as between the extreme positions shown in Figs. 3 and 6 is relatively small so that there is but little friction and wear occurring. With the valve in an intermediate position it will 70 be apparent that there is both inlet and exhaust communication with both of the openings 6 and 7 which in some cases is desirable in the operation of pneumatic hoists, for controlling the descent of the load on the 75 piston of the hoisting cylinder. When the valve is placed in the position shown in Fig. 7 it will be seen that fluid pressure may be retained by the valve in the pipes or ducts connected with both the openings 6 and 7, 80 since exhaust is prevented, and in this position there can be no passage of the fluid from the chest into either one of the openings 6 and 7.

Having thus described the invention, what 85 is claimed as new is—

1. In a valve, the combination of a cylindrical valve element having a centrally arranged stem on one side thereof and a centrally arranged cavity in the opposite side 90 thereof, the element having two channels extending at obtuse angles one to the other to a plane on one side of the axis of the stem, the element having also two ports extending therethrough in a plane on the opposite side of the axis, with a chest bottom rotatively supporting the said element and having three port openings arranged in the plane of said axis to be closed or opened by said element, said element being adapted 95 to slightly open all of said three port openings at one and the same time, and a chest having an opening through its wall secured to said bottom.

2. In a valve, the combination of a chest 105 bottom having a valve seat thereon and a guide shoulder extending about the seat, said bottom having two delivery openings therein and also an exhaust port opening between the delivery openings at the center 110 of said seat, said bottom having a joint seat beyond said shoulder, two conduits connected with the two delivery openings respectively, a valve chest secured to said bottom and having an annular projection seated on 115 said joint seat and having a packing box thereon, said chest having a guide wall therein, one side of said chest having a boss provided with an aperture therethrough, a supply pipe connected to said boss, a valve element having a flat face rotatably seated on 120 said valve seat and in contact with said guide shoulder and also in contact with said guide wall, said element having a central cavity in its face and two channels extending 125 from the cavity to a plane on one side of the center to form communication between said exhaust port and either one or both of said delivery openings, said element having also two ports extending there- 130

through in a plane on the opposite side of said center for opening communication between said chest and either one or both of said delivery openings, a stem secured to said element and extending through said packing box, and an operating arm adjustably secured to said stem.

In testimony whereof, we affix our signatures in presence of two witnesses.
